CLAIM

The ornamental design for a control panel for imaging device, as shown and described.

DESCRIPTION

FIG. 1 is a front elevational view of a control panel for imaging device showing our new design;
FIG. 2 is a back elevational view thereof;
FIG. 3 is a top plan view thereof;
FIG. 4 is a bottom plan view thereof;
FIG. 5 is a right-side elevational view thereof;
FIG. 6 is a left-side elevational view thereof; and,
FIG. 7 is a top, front, right-hand side perspective view thereof.
